(57) **CLAIM**

The ornamental design for a daytime running light arrangement for a vehicle front headlamp, as shown and described.

DESCRIPTION

FIG. 1 is a front and left side perspective view of a first embodiment for the daytime running light arrangement for a vehicle front headlamp;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a rear and right side perspective view thereof; and, FIG. 8 is a rear view thereof.

The broken lines in the drawings indicate a boundary residing between claimed and unclaimed portions and form no part of the claimed design. The claimed design is indicated by the portions shown within the broken line boundaries, while the deemphasized, grayscale portions shown outside of the broken line boundaries are environment and form no part of the claimed design. The claim includes a second embodiment comprised of a mirror image of the daytime running light arrangement for a vehicle front headlamp as shown in FIGS. 1-8.
